(57) **CLAIM**

The ornamental design for an interactive and multiservice digital terminal, as shown and described.

DESCRIPTION

FIG. 1 is a left side view of an interactive and multiservice digital terminal showing my new design; FIG. 2 is a right side view of the design shown in FIG. 1; FIG. 3 is a bottom view of the design shown in FIG. 1; FIG. 4 is a top view of the design shown in FIG. 1; FIG. 5 is a back view of the design shown in FIG. 1; FIG. 6 is a front view of the design shown in FIG. 1; and, FIG. 7 is a perspective view of the design shown in FIG. 1. The broken lines shown in the figures form no part of the claimed design and are included for the purpose of illustrating portions of the interactive and multiservice digital terminal that form no part of the claimed design.

1 Claim, 7 Drawing Sheets
